US0D1073021S

(12) **United States Design Patent** (10) **Patent No.:** **US D1,073,021 S**
(45) **Date of Patent:** **** Apr. 29, 2025**

(54) **BATHROOM FAUCET**

(71) Applicant: **Xiamen Lota International Co., Ltd.**,
Fujian (CN)

(72) Inventors: **Chuanbao Zhu**, Fujian (CN); **Liming Ye**, Fujian (CN); **Yunlong Xie**, Fujian (CN); **Fahong Chen**, Fujian (CN); **Yanping Yang**, Fujian (CN)

(73) Assignee: **Xiamen Lota International Co., Ltd.**,
Xiamen (CN)

(**) Term: **15 Years**

(21) Appl. No.: **29/845,468**

(22) Filed: **Jul. 7, 2022**

(30) **Foreign Application Priority Data**

Jan. 7, 2022 (CN) 202230009318.1

(51) **LOC (15) Cl.** **23-01**

(52) **U.S. Cl.**

USPC **D23/242**

(58) **Field of Classification Search**

USPC D23/238-244, 252, 254-255, 257;

(57) **CLAIM**

The ornamental design for a bathroom faucet as shown and described.

DESCRIPTION

FIG. 1 is an upper perspective view of a bathroom faucet according to the new design.

FIG. 2 is a lower perspective view of the bathroom faucet shown in FIG. 1.

FIG. 3 is a front view of the bathroom faucet shown in FIG. 1.

FIG. 4 is a rear view of the bathroom faucet shown in FIG. 1.

FIG. 5 is a right side view of the bathroom faucet shown in FIG. 1.

FIG. 6 is a left side view of the bathroom faucet shown in FIG. 1.

FIG. 7 is a top view of the bathroom faucet shown in FIG. 1; and,

FIG. 8 is a bottom view of the bathroom faucet shown in FIG. 1.

The broken lines in the drawings depict portions of the bathroom faucet that form no part of the claimed design.

1 Claim, 8 Drawing Sheets
